UNITED STATES PATENT OFFICE

94,985

DESIGN FOR AN AUTOMOBILE

Amos E. Northup, Pleasant Ridge, Mich., assignor to The Murray Corporation of America, Detroit, Mich., a corporation of Delaware

Application June 4, 1934, Serial No. 52,060

Term of patent 7 years

To all whom it may concern:

Be it known that I, Amos E. Northup, a citizen of the United States, residing in Pleasant Ridge, in the county of Oakland, State of Michigan, have invented a new, original, and ornamental Design for an Automobile, of which the following is a specification, reference being had to the accompanying drawing, forming a part thereof, wherein:

Figure 1 is a view in side elevation of an automobile embodying features of my design,

Fig. 2 is a front view of the automobile illustrated in Fig. 1 showing the relation of the hood with the lamps at the front end of the body, and

Fig. 3 is a perspective view of the front end of the automobile of Fig. 1 further illustrating the relation of the hood with the lamps.

The dominant feature of my design comprises that portion of the design illustrated in solid lines.

I claim:

The ornamental design for an automobile substantially as shown and described.

AMOS E. NORTHUP.
